LEWIS CHARLES LEWIS, OF COLUMBUS, OHIO, ASSIGNOR TO LLEWELLYN LEWIS, OF COLUMBUS, OHIO.

WATER-MOTOR.

1,191,011.

Specification of Letters Patent.

Patented July 11, 1916.

Application filed May 2, 1914. Serial No. 835,915.

To all whom it may concern:

Be it known that I, LEWIS C. LEWIS, a citizen of the United States, residing at Columbus, in the county of Franklin and State of Ohio, have invented a new and useful Water-Motor, of which the following is a specification.

This invention has reference to improvements in water motors of that type including a mechanically-actuated valve connected with the movable element of the motor, and a fluid-actuated valve coöperating with the first valve to control the admission and exhaust of the motive fluid.

The object of the invention is to improve and simplify the construction and operation of the valve mechanism of a motor of such type so that such mechanism may be inexpensive to manufacture and reliable and efficient in use and have but comparatively few parts.

In accordance with the present invention there is provided a cylinder with a power piston therein, and at one end of the cylinder are ducts and valves, one valve moving axially with reference to the other, and the two valves operating to control the flow of motive fluid and exhaust fluid, all the parts with the exception of the inlet and outlet members being of relatively small compass and of compact construction. The arrangement is such that the directing of the motive fluid to opposite sides of the power piston is controlled by a valve in turn actuated solely by the motive fluid, while in conjunction with such valve there is provided another valve having its part in the control of the direction of flow of the motive fluid, and the second named valve is under the control of the piston and timed in operation to be moved by the piston as the latter approaches its limit of reciprocatory travel.

The invention will be best understood from a consideration of the following detailed description, taken in connection with the accompanying drawings forming a part of this specification, with the further understanding that while the drawings show a practical form of the invention, the latter is not confined to any strict conformity with the showing of the drawings, but may be changed and modified so long as such changes and modifications mark no material departure from the salient features of the invention.

In the drawings: Figure 1 is a longitudinal diametric section of the improved motor, some parts being shown in elevation, and the piston approaching one limit of its travel. Fig. 2 is a longitudinal diametric section with some parts which are shown in section in Fig. 1 illustrated in elevation and with the piston and one of the valves at the other limit of travel from that shown in Fig. 1. Fig. 3 is a section on the line 3—3 of Fig. 2. Fig. 4 is a section on the line 4—4 of Fig. 2. Fig. 5 is a section on the line 5—5 of Fig. 2. Fig. 6 is a section on the line 6—6 of Fig. 1. Fig. 7 is a section on the line 7—7 of Fig. 1, some distant parts being omitted.

Referring to the drawings there is shown a cylinder 1, to one end of which there is applied an axially elongated head or valve casing 2. Within the valve casing 2 there is provided an axially located valve cylinder 4, which, as well as the head 2, is axially elongated so as to project for a distance into the corresponding end of the cylinder 1, and the valve cylinder 4 is made as long as the valve casing 2 with its prolongation entering the cylinder 1.

In part surrounding the cylinder 4 is a chamber 5 communicating with the interior of the cylinder 4 by way of a channel or port 6. Adjacent to the port 6, but separated from the chamber 5 by an annular web 7 is an annular port 8 communicating at one side with an outlet duct 9 terminating in a nipple portion 10 for connection to a pipe 80 or other means for disposal of the exhaust of the motor.

Partially surrounding that end of the valve cylinder 4 remote from the chamber 5 is another chamber 11 communicating with the interior of the cylinder 4 by way of an annular port 12, while the same end of the cylinder 4 communicates by way of a port or passage 13 with a chamber 14 into which an inlet duct 15 opens, this duct being provided with a nipple outer end 16 for the attachment of a pipe which may come from a suitable source of fluid under pressure, such fluid being usually water, and for convenience of description will be considered as water. The cylinder 4 also communicates with the chamber 14 through another port 17 on the side of the port 6 toward the cylinder 1. At that end of the valve casing entering the cylinder 1 the chamber 5 is annular, 110

2
and the outer walls of the chamber receive a cap 18 inclosing an annular chamber 19 surrounding an axially extended chamber 20 which is separated from the chamber 19 by 5 a cylindrical wall 21. The cap 18 is provided with an annular port 22 in line with the chamber 5, and opening into the chamber 19 so that the chamber 5 and the chamber 19 are constantly in communication. 10 The cap 18 has an interiorly threaded end 23 by means of which it is screwed onto the end of the valve casing entering the cylinder 1. The cylindrical wall 21 inclosing the chamber 20 is axially extended toward the bore of the cylinder 4 in the form of an 15 annular flange cut across at appropriate points, as shown at 23^a, for the flow of water through the walls of the flange. The wall 21 is continued axially beyond the cap 18 into the cylinder 1 and is formed with an 20 inwardly directed annular flange 24 forming a seat for a packing gasket 25 held in place by a ring nut 26, all for a purpose to be described. 25 Packing 27 is introduced between the cap 18 and the corresponding end of the valve casing, and packing 28 is introduced between the corresponding end of the cylinder 1 and the valve casing where the two join. That 30 end of the cylinder 1 remote from the valve casing 2 has a cap 29 applied thereto, which cap has an axial packing gland 30 and a packing gasket 31 is introduced between the cap 29 and the cylinder 1. Within this cylinder there is lodged a piston 32 which may be 35 composed of two plates 33, 34 holding cup-shaped packing rings 35 between them, and these plates may be secured together by screws 36 or otherwise. The plate 33 is 40 formed on one face with a hollow boss 37 having an axial passage 38 therethrough, while the other ring 34 is formed with a hollow boss 39 having a larger axial passage 40 therethrough. The boss 37 is internally 45 threaded for the reception of the corresponding end of a piston rod 41 having an axial bore 42 extending into it from the threaded end. This piston rod extends through the hollow boss 39 of the plate 34, and also is 50 continued to the exterior of the cylinder 1 through the packing gland 30.

Formed on the head 18 in eccentric relation to the axis thereof is a hollow boss 43 suitably threaded for the reception of a 55 pipe or tube 44 extending lengthwise of the cylinder 1 inside of said cylinder, and having the end remote from the boss terminating close to the interior of the head 29, the pipe being there freely open. 60 This pipe is extended through the piston 32 through appropriate matching passages eccentric to the longitudinal axis of the piston, and there the pipe is surrounded by packing rings 45 rendering the pipe exteriorly water 65 tight where it passes through the piston.

The pipe 44 is stationary while the piston is reciprocated in a manner to be described, but there is no appreciable leakage either by the piston or by the pipe 44 where passing through the piston. At that end of the valve casing 2 remote from the cylinder 1 there is applied a cap or head 46 having a reduced axial extension 47 constituting a prolongation of the cylinder 4, being in line therewith, and leading from the outer end of the prolongation 47 is a still further reduced axial extension 48 having the outer end 49 permanently closed. Where the extension 48 joints the prolongation 47 there is provided an annular flange 50.

Mounted to travel in the cylinder 4 is a valve 51 made up of tubular sections 52, 53 and 54. The section 52 terminates in axially extended nipples 55 and 56, and the section 54 terminates in axial nipples 57 and 58, each section 52, 53 and 54 being headed or radially expanded at the ends. The nipple 55 is exteriorly threaded for the reception of a ring nut 59 holding a packing ring 60 to the corresponding head of the section 52. The section 54 has its nipple 58 exteriorly threaded for the reception of a ring nut 61 holding a packing ring 62 against the corresponding head of the valve section 54. Applied to the nipples 56 and 57, which are exteriorly screw-threaded for the purpose, is the valve section 53, which latter is interiorly threaded to engage the nipples 56 and 57, and confines packing rings 63, 63 to the corresponding ends of the valve sections 52 and 54. Each nipple 55, 56, 57 and 58 is interiorly threaded for the reception of a ring-nut 64 holding a packing gasket 65 in place.

Extending through the valve 51 is a tubular valve member 66 considerably longer than the valve 51. This tubular member has one end 67 closed, and at an intermediate point is provided with a solid web 68, thus dividing the tube into two chambers 69 and 70, the latter having one end freely open. That end of the tubular valve member 66 remote from the chamber 70 is provided with a stem prolongation 71 of less diameter than the tubular valve, and of a size to pass snugly, yet freely, through the passage 38 in the boss 37, so as to enter the bore 42 in the corresponding end of the piston rod 41. That end of the stem 71 entering the piston rod is threaded, and has a nut 72 applied thereto, so that the piston rod is connected to the stem 71, and by it to the valve 66, but in a manner to provide for considerable movements of the piston without affecting the valve 66, so that the connection is of the lost motion type.

The valve 66 extends axially through the valve 51 with the packing rings or gaskets 65 snugly hugging it, but not sufficiently to prevent longitudinal movement of the valve 66 in the valve 51. The section 52 of the

5 valve 51 has a sufficiently large internal diameter to provide a chamber 73 within it about the valve 66. The section 53 provides a similar interior chamber 74 and the valve section 54 also incloses a chamber 75 about the valve 66. The valve section 52 has ports 76 through its walls between its heads, the valve section 53 has ports 77 through its walls between its heads, and the valve section 10 54 has ports 78 through its walls between its heads. The valve 66 has ports 79 through its walls near the closed end 67, other ports 80 through its walls near the web 68, and both sets of ports 79 and 80 open into the 15 chamber 69, while on the other side of the web 68 the valve 66 has ports 81 opening through its walls into the chamber 70. Between the cap 46 and the corresponding end 20 of the valve casing 2 packing 82 is provided, so that the various chambers, the ends of 25 which are closed by the cap 46, do not inter-communicate.

In the position of the parts shown in Fig. 1, it is assumed that the piston has been moving on the power stroke toward the right until the inner wall of the boss 37 has engaged the nut 72, so that a continuance of such power stroke will cause a corresponding movement of the valve 66. During this 30 power stroke water has been flowing through the conduit 15 into the chamber 14, and by way of the port 13 into the valve cylinder 4, finding its way through the port 12 into the chamber 11 in the valve casing, which chamber is in constant communication with the cylinder 1 through an extension 11^a. Water under pressure also finds its way from the interior of the valve cylinder 4 after entering the same through the port 12, through 35 the ports 76 into the chamber 73, and from the latter by the ports 81 into the chamber 70, escaping through the open end of the valve 66 into the interior of the extension 48, and from the latter into the interior of 40 the prolongation 47, and bearing against the corresponding end of the valve 51, maintaining this valve in the right hand position shown in Fig. 1. While the piston is moving toward the right water from in front of 45 it escapes through the pipe 44 into the boss 43, hence into the chamber 5, through the port 6 into the cylinder 4, about the valve section 53, and by way of the port 8 of the outlet 9.

50 As the piston 32 continues its stroke toward the right the valve 66 is carried with it until the ports 81 open into the chamber 74 and the ports 80 open into the chamber 75. When this occurs the interior of the 55 prolongation 47 and extension 48 are put into communication with the exhaust side of the motor by way of the chamber 70, ports 81 and chamber 74 which is in communication with the exhaust through the ports 77.

60 Now, pressure through the chamber 14 by

way of the port 17 is exerted upon the valve section 54 and the water finds its way through the ports 78, through the chamber 75, and by way of the ports 80 into the chamber 69, and by way of the ports 79 into the chamber 20, so that the water pressure is exerted upon the right hand end of the valve 51, the water pressure being otherwise balanced upon this valve, wherefore the valve is forced toward the left as far as 75 it can travel, as shown in Fig. 2. Now, the water under pressure finds its way from the chamber 14 through the port 17 into the cylinder 4 about the valve section 54, and by way of the port 6 into the chamber 5, which 80 is in constant communication with the chamber 19, wherefore water under pressure finds its way by the pipe 44 to the right hand end of the cylinder 1 and the pressure is exerted on the corresponding face of the 85 piston 32, causing the latter to travel toward the left. Water from the left hand end of the cylinder 1 now finds escape by way of the chamber 11 through the port 12 to that part of the cylinder 4 with which the valve 90 section 53 is then coincident, and the water flows into the space surrounding the valve section 53 and out through the port 8 into the outlet 9. This continues until the piston has traveled nearly to the limit of its left 95 hand stroke as viewed in Fig. 1, when the boss 37 engages the end 67 of the valve 66, then projecting beyond the boss or extension 24 and forces the valve 66 toward its first position, which position is shown in Fig. 1, 100 whereupon the direction of flow of water under pressure as exerted upon the valve 51 is reversed, and the valve 51 is returned to the position shown in Fig. 1 so that the piston 32 is again forced toward the right. 105 The operation is entirely automatic and continues indefinitely so long as water under suitable pressure is supplied.

If it be desired to dismantle the structure for inspection or repairs, it is merely necessary to remove the cap or head 29, unscrew the piston rod, and remove the nut 72, and then by unscrewing the cap 46 both valves are freely accessible for the removal of either the valve 66, or both valves 66 and 51. 115

What is claimed is:—

1. In an apparatus of the class described, a cylinder, a reciprocatory piston therein, a valve casing at one end of and aligned with the cylinder, a reciprocatory valve responsive to fluid pressure, and mounted in the valve casing concentric therewith, another reciprocatory valve in and concentric with the first-named valve and connected to the piston for actuation thereby, said valves and 120 valve casing having ports for the flow and control of motive fluid, and a pipe within the cylinder extending through the piston with one end of the pipe communicating with the valve casing and the other end 125 130

opening into the cylinder on the side of the piston remote from said valve casing.

2. In an apparatus of the class described, the combination of a cylinder, a reciproitable piston mounted therein, a valve casing connected with the cylinder, conduits communicating with the valve casing and the opposite ends of the cylinder, the conduit connecting the casing to the end of the cylinder remote therefrom being located within the cylinder, inlet and outlet chambers for the casing, a fluid-actuated valve mounted for reciprocation in the casing controlling the flow of fluid through said conduits to reciprocate the piston, a mechanically-actuated valve axially located with respect to the fluid-actuated valve for admitting fluid to opposite ends of the casing to operate the fluid-actuated valve, and a lost-motion connection between the piston and the mechanically-actuated valve, the conduit for directing fluid to the end of the piston remote from the valve casing extending through said piston.

3. In a fluid motor, a motor cylinder, a piston therein, a valve casing at one end of and connected with the cylinder and in turn inclosing a cylinder of even internal diameter throughout, a removable closure for the end of the valve casing and second-named cylinder remote from the motor cylinder and containing a cylinder forming a continuation of the second-named cylinder and together with the latter constituting a valve cylinder of even internal diameter throughout, a mechanically actuated valve of even diameter throughout extending centrally through the valve cylinder and provided at one end with a connection to the piston, and a fluid actuated valve located and reciprocable wholly within the valve cylinder and surrounding the first-named valve, said second-named valve comprising spaced end members and a central member connecting them, spaced packing means carried by the end members exterior thereto and in position to engage the inner wall of the valve cylinder, and other packing means also carried by each end member at each end thereof interior to the second-named valve and in position to engage the outer wall of the first-named valve, said first-named packing means coacting with the corresponding valve members of the fluid actuated valve and with the valve cylinder to define chambers, and said second-named packing means coacting with the valve members of the fluid actuated valve and the first-named valve to define chambers.

4. A fluid motor having a motor cylinder, a piston therein and a valve casing at one end inclosing a valve cylinder, a longitudinally extended valve of even diameter throughout located in the valve cylinder with the latter also of even internal diam-

eter throughout and said valve being provided with a mechanical connection to the piston, and a second named valve within the valve cylinder surrounding and movable along the first-named valve and comprising 70 end members each interiorly and exteriorly threaded and shouldered at both ends, and a central member interiorly threaded at both ends and coacting with the exterior shoulders at the corresponding inner ends 75 of the other members to unite the latter and confine packing against the shoulders, nuts for the outer threaded ends of the first-named members coacting with the shoulders thereat for confining packing thereagainst, 80 and means for confining other packing within both end portions of each end member in engagement with the first-named valve, whereby there are formed as many chambers between the fluid actuated valve and the valve casing and also between the two valves as there are members of the fluid actuated valve.

5. A fluid motor having a motor cylinder with a removable head at one end and a piston within the cylinder provided with a piston rod connected thereto for removal therefrom without dismantling the piston, said fluid motor being also provided with a valve casing at the end of the cylinder 95 remote from the removable head and containing a valve cylinder of even diameter throughout and having a removable closure at the end remote from the motor cylinder, a mechanically-actuated valve of even diameter throughout extending through the valve cylinder and having a mechanical connection to the piston for removal therefrom on the removal of the piston rod from the piston, and a second valve surrounding 100 the first-named valve and located and working wholly within the valve cylinder, whereby either or both valves are bodily removable from and introducible into the valve cylinder through that end thereof provided 105 with the removable closure.

6. In a fluid motor, a motor cylinder having a removable head at one end, a piston in the cylinder, a piston rod connected to the piston for attachment to and removal therefrom while the piston is in the cylinder and without dismantling the piston, a valve casing at the end of the cylinder remote from the removable head and having a valve cylinder of even diameter throughout in axial alignment with the motor cylinder, a tubular valve of even diameter throughout working in and extending through the valve cylinder and provided with a mechanical connection removably joined to the piston and there accessible on the removal of the cylinder head and the piston rod from the piston, a second valve surrounding the tubular valve and located wholly within the valve cylinder and provided with exterior packing 110

5 rings engaging the walls of the valve cylinder, and other interior packing rings engaging the walls of the tubular valve, and a removable cap for that end of the valve casing remote from the motor cylinder, whereby either or both valves may be bodily removed from and introduced into the valve cylinder through the end of the valve casing provided with the removable 10 cap.

15 7. A water motor comprising a cylinder, a piston therein, a valve casing connected to one end of the cylinder, a head on one end of the valve casing within the cylinder, a tubular conduit communicating with the valve casing and extending from the head thereof through the piston into juxtaposition with the other end of the cylinder, a re-

movable cap member for the end of the valve casing remote from the cylinder, said 20 valve casing having an axially elongated valve cylinder therein in line with the longitudinal axis of the first-named cylinder, a tubular valve mounted therein and connected with the piston, and another valve 25 mounted in the valve cylinder and movable along the tubular valve, said valves and the valve casing having chambers and ports for the control of motive fluid.

In testimony, that I claim the foregoing 30 as my own, I have hereto affixed my signature in the presence of two witnesses.

LEWIS CHARLES LEWIS.
